HYDRAULIC SURFACE GRINDING MACHINE

Herbert A. Silven, Worcester, Mass., assignor to
 Norton Company, Worcester, Mass., a corpora-
 tion of Massachusetts

Application January 23, 1942, Serial No. 427,955

3 Claims. (Cl. 60—52)

The invention relates to grinding machines, and more particularly to a hydraulically operated surface grinding machine for grinding plane surfaces on a work piece.

One object of the invention is to provide a simple and thoroughly improved hydraulically operated surface grinding machine. Another object of the invention is to provide an improved hydraulically operated surface grinding machine in which the work table is reciprocated longitudinally by an hydraulically operated mechanism and the wheel slide is indexed or traversed transversely by an hydraulically operated mechanism which is controlled by and in timed relation with the table reciprocating movement.

A further object of the invention is to provide a hydraulically operated table reciprocating mechanism which may be stopped precisely in a predetermined position. A further object of the invention is to provide a hydraulically operated table traversing mechanism in which means are provided to supply fluid to the fluid pressure delivery pipe line after the pressure fluid from the fluid pump is cut off to prevent creeping of the table in the reverse direction.

Another object of the invention is to provide a hydraulically operated table reciprocating mechanism with a connection including a check valve between the reservoir and the fluid pressure delivery pipe line to prevent the creation of a vacuum within the table cylinder so that the table may be stopped in a predetermined position for a grinding wheel truing operation. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawing in which is shown one of various possible embodiments of the mechanical features of the invention,

The figure is a diagrammatic view, showing the hydraulically operated control system and actuating parts.

A surface grinding machine has been illustrated in the drawing, comprising a base 10 having a longitudinally reciprocable work supporting table 11 supported on the usual V-way and flat way (not shown) on the base 10. A grinding wheel 12 is rotatably mounted on a transversely movable wheel slide (not shown) which is supported on a vertically movable slide (not shown) car-

ried by an upwardly extending portion of the base 10.

The grinding wheel feeding mechanism is preferably of a type similar to the well known feeding mechanism such as shown in the prior U. S. Patent to Norton, No. 1,108,779 dated August 25, 1914, and the U. S. Patent to H. A. Silven, No. 2,269,697 dated January 13, 1942.

A hydraulically operated mechanism is provided for reciprocating the table 11 to reciprocate the work piece 16 beneath the operative face of the grinding wheel 12. In the preferred form the reciprocating mechanism may comprise a cylinder 21 which is fixedly mounted within the base 10 of the machine. A piston 22 is slidably mounted within the cylinder 21 and is connected to one end of a piston rod 23. The other end of the piston rod 23 is connected to a bracket 24 depending from the under side of the table 11. The base 10 is provided with a reservoir 25 from which fluid may be pumped through a pipe 26 by means of a motor driven fluid pump 27. The pump 27 forces fluid under pressure through a pipe 28 to a main control valve 30. A pressure relief valve 31 is provided in the pipe line 28 whereby excess fluid under pressure may be passed directly through a pipe 32 into the reservoir 25.

The main control valve 30 is a piston type valve comprising a valve stem 33 having formed integrally therewith valve pistons 34, 35 and 36. The main control lever 37 is pivotally supported by a stud 38 which is carried by a bracket 39. The bracket 39 is fixedly supported on the front of the machine base. The lever 37 is connected by a pair of diametrically opposed, spaced, aligned pins 40 with a spool-shaped member 41 mounted on the outer end of the valve stem 33. It will be readily apparent from the foregoing disclosure that movement of the control lever 37 serves to shift the valve stem 33 to change the position of the valve pistons as desired. In the position of the valve 30 shown in the figure, fluid under pressure passing through the pipe 28 enters a valve chamber 42 located between the valve pistons 34 and 35 and passes out through a pipe 43 to the reservoir 25.

When it is desired to start the reciprocatory movement of the table 11, the main control lever 37 is moved in a counterclockwise direction so that fluid under pressure from the pump 27 and pipe 28 enters a valve chamber 44 located between the valve pistons 35 and 36 and passes out through a pipe 45 to a table reversing valve 46. Fluid from the pipe 45 enters a chamber (not shown) in the rear portion of the table reversing

valve 46 and passes through a central aperture 47 in a frusto-conical rotary reversing valve member 48. Fluid passing through the passage 47 in the reversing valve member 48 is admitted either through a port 49 or a port 50 in the reversing valve casing 51. Fluid under pressure passing through either the port 49 or the port 50 passes through pipe 52 or a passage 53, respectively, to the table cylinder chambers 54 and 55, respectively, to move the piston 22, the piston rod 23, and the table 11 in a longitudinal direction. In the position of the valve 46 shown in the figure, fluid under pressure passes through the pipe 52 into the cylinder chamber 54 to move the piston 22, the piston rod 23, and the table 11 toward the right. During this movement, fluid within the cylinder chamber 55 exhausts through the passage 53, the port 50, and through an exhaust passage 56 in the valve member 48 and passes out through a passage 57 and a pipe 58 to the reservoir 25.

The reversing valve member 48 may be actuated either manually or by power. As illustrated in the drawing, a manually operable reversing lever 60 is pivotally mounted on a stud 61 which is fixedly mounted relative to the base 10. A depending portion of the reversing lever 60 is provided with a gear segment 62 which meshes with a gear segment 63. The gear segment 63 is mounted on the outer end of a rock shaft 64. The inner end of the rock shaft 64 supports a gear segment 65 which in turn meshes with a gear (not shown) mounted on the end of the valve stem (not shown) which is formed integral with the reversing valve member 48.

It will be readily apparent from the foregoing disclosure that when the reversing lever 60 is rocked, motion will be transmitted through the mechanism above described to actuate the reversing valve member 48. In order that the reversing valve may be automatically and rapidly shifted into a reverse position after the reversing lever 60 has moved to a central position, a load and fire mechanism is provided. The gear segment 65 is provided with a downwardly extending arm 70 which serves as a support for a stud. The stud rides in an elongated slot 72 formed in the upper end of a rock arm 73. The rock arm 73 is pivotally supported on a stud 74. A tension spring 75 is connected at its lower end to a stud 76 carried by the rock arm 73 and its upper end is fastened to a stud which is fixed relative to the base of the machine. This mechanism is substantially identical with that shown in the prior U. S. Patent to Carl G. Flygare and Wallace H. Wood, No. 2,022,542 dated November 26, 1935, to which reference may be had for disclosures not contained herein. It will be readily apparent from the foregoing disclosure that when the reversing lever 60 is shifted, it will transmit a corresponding movement in the reverse direction to the rock arm 73 which increases the tension on the spring 75. After the stud 76 passes by a central position, the released tension of the spring 75 rapidly shifts the lever 60 and gear mechanism above described to shift the reversing valve member 48 into a reverse position to reverse the flow of fluid under pressure to the chambers of the cylinder 21.

The reversing lever 60 may be actuated manually or may be actuated in timed relation with the reciprocatory movement of the table 11 by a pair of reversing dogs 77 and 78 which are adjustably supported in a T-slot 79 formed in the front edge of the work table 11. The length of

the reciprocatory stroke of the table 11 may be readily adjusted by shifting the table dogs 77 and 78.

In truing the grinding wheel 12, a truing tool 5 and holder are mounted upon the work table 11 and the table is then moved longitudinally to position the truing tool directly under the grinding wheel, in which position the table is stopped for a truing operation. In using a hydraulically driven table reciprocating mechanism such as that shown in the present case, there is a tendency for the table 11 to creep in the opposite direction when it has been stopped, thus preventing precise location of the truing tool relative to the grinding wheel. In order to prevent a creeping movement of the table 11 in the opposite direction when it is stopped, a pipe line 80 is connected with the fluid pressure delivery pipe line 45 at a point adjacent to the table reversing valve 46. A check valve 81 is mounted at the lower end of the pipe 160 and has a short pipe 82 extending into the lower part of the reservoir 25.

Assuming the table 11 to be traveling in a direction toward the right, that is, with the main control lever 37 shifted in a counterclockwise direction, fluid under pressure from the pump 27 and pipe 28 passes through the pressure delivery line 45 to the table reversing valve 46 and through the central chamber 47 of the rotatable reversing valve member 48 and passes out through the pipe 52 into cylinder chamber 54 to move the piston 22 and table 11 toward the right.

When it is desired to stop or to reverse the direction of table movement, the main control lever 37 is shifted in a clockwise direction into the position shown in the figure, which movement shifts the valve stem 33 so as to cut off the passage of fluid under pressure through the fluid pressure delivery pipe 45, as above described. Due to the inertia of the rapidly moving table 11, the table 11 together with the piston 22 tends to continue its movement toward the right after the fluid under pressure is cut off, thus tending to create a vacuum in the cylinder chamber 54. As the piston 22 continues its movement toward the right, a suction effect is obtained which draws fluid directly from the reservoir 25 through the check valve 81, into the pressure delivery pipe line 45 and valve 46 into the chamber 54, thus maintaining the chamber 54 filled with fluid so that there is no vacuum created which will cause a creeping of the table 11 in the reverse direction thereto.

The operation of this machine will be readily apparent from the foregoing disclosure. The table 11 is reciprocated in the manner above described. Assuming the various valves to be adjusted into the positions illustrated, the table 11 is stationary. When it is desired to start the table movement, the main control lever 37 is moved in a counterclockwise direction to shift the valve stem 33 so that fluid under pressure from the fluid pump 27 and the pipe 28 may pass through the main control valve 30 and out through the fluid pressure delivery line 45 to the table reversing valve 46. This fluid under pressure will pass through the valve 46, the pipe 52, into the cylinder chamber 54 to cause the piston 22 and table 11 to move toward the right. This movement will continue until the table dog 77 engages the reversing lever 60 and shifts the table reversing valve 46 into its reverse position to change the direction of flow of fluid under pressure so that it will enter through the pas-

sage 50 into the cylinder chamber 55 to move the piston 22 and the table 11 toward the left.

When it is desired to true the grinding wheel 12, a truing tool (not shown) may be positioned on the table 11 and the table traversed to locate the diamond directly below the grinding wheel 12, that is, with the cutting point of the diamond in a vertical plane passing through it and the axis of the grinding wheel. When the table 11 reaches approximately this position, the main control lever 37 is thrown in a clockwise direction into the position shown in the figure to cut off the flow of fluid under pressure through the delivery pipe 45, thus stopping the table movement and thus tending to create a vacuum in the chamber where the pressure has just been cut off, at which point a suction is created within the pipe 80 to draw fluid from the reservoir 25, through the pipe 82 and check valve 81, into the cylinder chambers 54 or 55, depending upon the direction of reciprocatory movement of the table 11. Thus no actual vacuum is created and there is no tendency of the table to creep in a direction toward the left if the table reciprocation is to the right as shown in the figure, thus facilitating stopping the table in a precise and predetermined position for a truing operation.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawing is to be interpreted as illustrative and not in a limiting sense.

I claim:

1. In a grinding machine having a longitudinally reciprocable table, means including a piston and cylinder to reciprocate said table, a fluid reservoir, means including a fluid pressure pump to convey fluid under pressure from said reservoir to said cylinder, a reversing valve located between the pump and cylinder to control the admission to and exhaust of fluid from said cylinder,

inder, a start and stop valve to start and stop said table reciprocation, and means including a check valve which is connected between the reservoir and the reversing valve to admit fluid directly from the reservoir to the pressure port of the reversing valve to prevent creeping of the table in the reverse direction when the stop and start valve is closed to stop the movement of the table.

2. In a grinding machine having a longitudinally reciprocable table, means including a piston and cylinder to reciprocate said table, a fluid reservoir, means including a fluid pressure pump to convey fluid under pressure from said reservoir to said cylinder, a reversing valve located between the pump and cylinder to control the admission to and exhaust of fluid from said cylinder, a start and stop valve located between the pump and the reversing valve to start and stop the table reciprocation, and means including a check valve which is connected between the reservoir and the reversing valve to admit fluid directly from the reservoir to the pressure port of the reversing valve to prevent creeping of the table in the reverse direction when the stop and start valve is closed to stop the movement of the table.

3. In a grinding machine having a longitudinally reciprocable table, means including a piston and cylinder to reciprocate said table, a fluid pressure system including a motor driven pump, a reversing valve to control the admission to and exhaust of fluid from said cylinder, a fluid pressure delivery pipe line connecting said pump and said reversing valve, a manually operable start and stop valve located between the pump and the reversing valve to facilitate starting and stopping the reciprocatory movement of the table, and means including a normally closed check valve connected between the reservoir and the fluid delivery line adjacent to said reversing valve which is arranged to open and draw fluid directly from the reservoir to prevent a creeping movement of the table in the reverse direction when the stop and start valve is shifted to stop the movement of the table.

HERBERT A. SILVEN.
